W. F. JENKINS.
DEMOUNTABLE RIM.
APPLICATION FILED OCT. 7, 1912.

1,076,430.

Patented Oct. 21, 1913.

Fig. 1.

Fig. 3.

A technical drawing of a curved structure, likely a bridge arch, showing dimensions and labels. The structure is labeled with '5' and '3rd' at the top left, '6' and '0th' at the top right, and '1' and '3rd' at the bottom left. The bottom right is labeled '3'. The drawing includes a central vertical axis and various hatching patterns.

WILTON F. JENKINS
BY *W. F. Jenkins*

UNITED STATES PATENT OFFICE.

WILTON FORD JENKINS, OF RICHMOND, VIRGINIA.

DEMOUNTABLE RIM.

1,076,430.

Specification of Letters Patent.

Patented Oct. 21, 1913.

Application filed October 7, 1912. Serial No. 724,315.

To all whom it may concern:

Be it known that I, WILTON F. JENKINS, a citizen of the United States, and a resident of Richmond, in the county of Henrico 5 and State of Virginia, have made certain new and useful Improvements in Demountable Rims, of which the following is a specification.

My invention relates to improvements in 10 demountable rims, and it consists in the combinations, constructions and arrangements herein described and claimed.

An object of my invention is to provide 15 a device which is of simple construction, but which will positively hold the demountable rim in place when the latter is secured to the fixed rim.

A further object of my invention is to 20 provide a demountable rim which is split at one portion thereof, with means adjacent to the split portion for drawing the latter tightly together and firmly holding it in place.

Other objects and advantages will appear 25 in the following specification, and the novel features of the device will be particularly pointed out in the appended claim.

My invention is illustrated in the accompanying drawings forming part of this application in which—

Figure 1 is a face view of a wheel, showing the rims assembled, Fig. 2 is a circular section through a portion of the fixed and demountable rims, Fig. 3 is a transverse 35 section along the line 3—3 of Fig. 1, Fig. 4 is a plan view of a portion of the fixed rim, and Fig. 5 is a plan view of a portion of the demountable rim.

In carrying out my invention I make use 40 of a wheel of the ordinary type having a hub 1, spokes 2, and a felly 3. On the exterior portion of the felly is mounted a fixed rim 4, which is preferably made of metal, and which is provided with an outwardly 45 turned flange 4^x. The rim 4 is provided with a pair of lugs or wedges 5, which are inclined toward each other, these lugs being nearer together at the flange 4^x, as shown in Fig. 4. The inner edges of the lugs 5 are 50 beveled from their outer surfaces inwardly toward the surface of the rim 4, as shown in Fig. 2.

The demountable rim 6 is provided with 55 the curved flanges 6^x. It is split diagonally, as shown at 6^b, so as to provide overlapping portions. On each side of the split are lugs

or wedges 7, whose outer edges 7^x are beveled to engage the beveled edges of the lugs 5, as shown in Fig. 2.

In order to hold the demountable rim to 60 the fixed rim I provide wedges like those shown at 8 in Fig. 3. These wedges are disposed between the flange 4^x of the fixed rim and the flange 6^x of the demountable rim. Bolts 9 pass through recesses 9^x in the felly 3, and are provided with heads 10 of the shape shown in the drawings. These heads engage the fixed rim on one side of the bolt and the felly on the other side, thus 65 securely holding the wedges in position.

From the foregoing description of the 70 various parts of the device the operation thereof may be readily understood. The rim is split diagonally, as shown at 6^b so that the rim can be made smaller to facilitate the 75 putting on of the tire.

In assembling the device the tire 11 is 80 first placed on the demountable rim and blown up. This will tend to bring the two portions of the split, demountable rim together. In order that these portions may be kept in alinement I provide a stop member 12, which is riveted to the under side of one of the ends of the split rim, and which is arranged to project underneath the other 85 end, so that when the tire is blown up and the parts are drawn together the edges of the split rim will be in exact registration. The demountable rim is now slipped on to the fixed rim from that side opposite the 90 flange 4^x and the wedges 5 are thus brought into registration with the wedges 7 in the manner shown in Fig. 2. A wedge 8 is now 95 inserted between the two wedges 7 on the demountable rim and the nut 9^y on the bolt 9 is tightened so as to secure the wedge in place. The wedges 8 around the wheel are secured in place, and the device is ready for use.

It will be observed that the provision of 100 the wedge 8 prevents any movement of the ends of the detachable rim toward one another, therefore there is no danger of the two ends of this rim becoming detached. The fact that the wedges are inclined pre- 105 cludes any chance of movement of the demountable rim in a lateral direction toward the flange 4^x, while the bolts and their heads 10 prevent any movement in the opposite direction.

The parts are few in number, and are 110 therefore not liable to get out of order, but

the device is easily manipulated and positively holds the two rims together.

I claim:

The combination with a felly, of a fixed rim secured thereto and provided with a pair of converging lugs, and a split, demountable rim having a pair of converging lugs disposed on the opposed ends of said split rim and arranged to engage the lugs 10 on said fixed rim, the adjacent faces of the

lugs of said fixed rim being beveled from their outer surfaces toward the body of the fixed rim, and the lugs of the demountable rim being beveled in the opposite direction to engage and be held by the beveled portions of the lugs of the fixed rim. 15

WILTON FORD JENKINS.
